DESIGN FOR A CLOCK CASING

Max Schlenker, La Salle, Ill., assignor to General
Time Instrument Corporation, New York,
N. Y., a corporation of Delaware

Application July 29, 1937, Serial No. 70,720

Term of patent 7 years

To all whom it may concern:

Be it known that I, Max Schlenker, a citizen of the United States, residing in the city of La Salle, in the county of La Salle and State of Illinois, have invented a new, original, and ornamental Design for a Clock Casing, of which the following is a specification, reference being had to the accompanying drawing, forming a part thereof.

Fig. 1 is a perspective view of a clock casing, showing my new design.

Fig. 2 is a front view of my clock casing.

Fig. 3 is a side view of my clock casing.

Figs. 2 and 3 are on a reduced scale in comparison with the disclosure in Fig. 1.

Fig. 4 is a side elevational view of the clock casing, partly in section.

In my clock casing the front larger circular part is made of a transparent material and made up of a plurality of circular transparent plates, the front one of which is clear and the transparent plate in the rear adjacent to the transparent front plate has a slight tinge of color contrasting with the colors of the other plates.

I claim:

The ornamental design for a clock casing, as shown and described.

MAX SCHLENKER.
